TO SIMMONS COMPANY, OF KENOSHA, WISCONSIN, A CORPORATION OF DELAWARE.

PACKAGING BEDSTEAD FRAME.

Application filed April 17, 1922. Serial No. 553,813.

Our invention relates to improvements in the art of packaging bedstead frames, and relates particularly to the manner of so packing a bedstead frame that the same may be delivered to the ultimate consumer in the same condition in which it leaves the factory of the manufacturer.

The principal objects of the invention are to provide a bedstead package of unitary character which shall contain a pair of head and foot-end-frames or panels so arranged that damage by shipment or otherwise shall be reduced to a minimum; to provide a package containing a bedstead frame in which the use of dust or dirt producing packing material such as excelsior, is eliminated; to provide means for so anchoring the parts of the bedstead frame within an enclosing container that the parts will not rub against each other or against the inner surface of the container; to provide means for mutually supporting the parts of the bedstead; to provide a construction of package which shall be simple and inexpensive to produce; and in general, to provide a neat, rugged and efficient package of the character referred to.

In the drawings which illustrate our invention as applied to the packaging of a bedstead frame comprising a pair of head and foot-end-frames or panels:

Fig. 1 is a side elevation of a completed package;

Fig. 2 is a plan view of said package showing the frames in place and with the flaps of the package open prior to their being sealed in place;

Fig. 3 is a section taken on the line 3—3 of Fig. 1;

Fig. 4 is a section taken on the line 4—4 of Fig. 1;

Fig. 5 is a fragmentary enlargement of a portion of Fig. 2;

Fig. 6 is a section taken on the line 6—6 of Fig. 3; and

Fig. 7 is a view similar to Fig. 4 showing the application of the invention to a bedstead frame constructed with round instead of square steel metallic tubing.

Referring to the drawings, it will be ob-

served that the bedstead frame therein shown comprises a head-end-frame or panel constructed, in this instance, of metallic tubing of square cross section. The outer boundary of said head frame consists of what in the trade is known as a "continuous post" which in reality comprises a top rail portion 10 integrally connected by means of bends 11 to the corner-posts 12. The top rail 10 of the panel or frame constitutes an upper support 60 for the filler tube 13, the lower ends of which are supported in or secured to the lower rail 14.

The foot-end-frame or panel is of substantially the same construction as the head-end-frame or panel just described, but in the case of the foot-end the post portions 15, as is usual in the art, are considerably shorter than the head-end post portions 12. Also, in order to provide a more finished or artistic appearance, the lower ends of the foot-end post portions are equipped with ornamental legs, as at 16. The lower ends of the leg portions 16 are hollow and are adapted to receive sockets provided with bottom 75 plates 17 suitably apertured and otherwise constructed to admit the stems of the casters. The four casters, according to the usual practice, are tied together in a bundle, which bundle is suitably secured to some part of 80 one of the frames so as not to rattle around in the package during shipment, and thereby to injure the finish of the bedstead.

Both the head-end post portion 12 and the foot-end post portion 15 are constructed with 85 brackets, as at 18, 19, 20 and 21, said brackets having means for detachably securing in place the angle-iron side-rails (not shown) usually shipped separately outside of the bedstead package, and which serve to connect together the head and foot-end panels of the bedstead and also to support the spring or bed bottom.

In preparing the package, we first procure a pair of spacing blocks or posts 22, 95 for instance, short wooden rods or bars, in the ends of which there are inserted small headless pins, as at 23 and 24. The lower pins 23 are arranged to enter small apertures punched or drilled into the top flange 100

or web 25 of the brackets 18 and 19. The pins 24 in the upper ends of the spacing rods 22 are adapted to enter the apertures in plates 17 through which the stems of the casters are to be inserted when setting up the bedstead.

The length of the spacing rods 22 is such that when the foot-end-panel is placed parallel with the head-end-panel, but at a 10 slight distance therefrom, and with its brackets 20 and 21 facing in the same general direction as the brackets 18 and 19, the top of the upper rail 26 which connects the post portions 15 will be positioned at the 15 same height and will parallel or overlie the top rail 10 of the head-end-frame or panel.

Suitable clamps arranged in pairs, the pairs in the present instance, being four in number, are employed to hold and maintain 20 the head-end-panel and the foot-end-panel in properly spaced parallel relation during shipment, and also serve to space the frames away from the walls of the container. Preferably two of said pairs of clamps, as 25 indicated in Fig. 6, are symmetrical as to their opposite ends, while the upper pairs of clamps, as illustrated in Fig. 4, are made with extensions.

As shown in Figs. 4, 5 and 6, each member 30 of each pair of clamps comprises a block of material such as wood, which is relatively cheap and light in weight, the inner surface of said wood block 27 being notched out to form a pair of grooves of the required width 35 and shape to admit the tube or other member to which the clamp is applied. Preferably in order to prevent the panels from moving towards each other, the grooves or notches in the faces of the clamps are separated by a tongue or rib 28.

The two parts or members of each clamp pair are preferably of the same shape and size and are secured together by means of a central clamping bolt 29. Ordinarily it 45 will be of advantage to countersink the outer member of the pair of clamps in the manner indicated at 30 in Fig. 6 and 31 in Fig. 4 in order to prevent the head 32 of the clamping bolt 29 from projecting from 50 the outer surface of the clamp. Owing to the fact that the nut 33 on the threaded end 34 of the clamping bolt 29 is usually arranged toward the inside of the clamp, said 55 nut and threaded end of the bolt may project without bad effect.

As we have found that the wooden clamps when bolted directly to the posts of the bedstead have a tendency to injure or mar the painted, enameled, varnished, or lacquered 60 surface of the bedstead, we find it desirable to interpose between the bedstead frame portions and the clamping faces of the clamp members some lining material which will prevent the wood from coming in direct 65 contact with the finish. Such lining takes

the form of a sheet or strip fitting in the bottoms of the notches of each clamp member, as indicated at 35. Preferably the sheet portions which line adjacent notches in the same clamp member are integrally connected together by a connecting portion 36 extending over and around the tongue 28 and apertured to receive the bolt 29 so that the bolt 29 will prevent the lining strips from shifting when the package is being assembled or in transit.

The packing or lining material 35 should, of course, be selected in accordance with the character of the finish of the bedstead and also in accordance with the condition to which the package will be subjected during storage or shipment. For instance, under certain conditions it may be possible to use merely strips of felt, heavy waxed paper, or even cardboard. However, in order to avoid the possibility of marring the finish, we prefer to use strips of sheet celluloid which preferably have been previously dusted with powdered talc or soap-stone. We do not claim to be the inventors of this special material.

We have previously referred to the fact that the pairs of clamps which secure together the top rails of the foot-end and head-end-frames are longer than the side 25 clamps. Said extensions 37^a are for the purpose of bringing the ends of the upper clamps to the side surface of the wall of the container so that the upper ends of the bedstead frames or panels will not move sideways in the package. It may be stated here that the thickness or space between the walls of the container which we will hereafter describe, is determined by the amount of projection of the brackets 20 and 21 of the foot-end-panel. The extent of projection 37 and 37^a of the ends of the clamp members obviously is also a factor to be considered in arriving at the dimensions of the container. The amount of projection 37 and 37^a is preferably determined by the stiffness of the material of which the outer enclosure or carton is constructed, it being, of course, understood that no portion of the finished surface of the bedstead frames should be allowed to 100 contact with the inner surface of the container during shipment or storage of the package.

In practice we prefer to make the outer 105 container or enclosure for the package of a very heavy grade of stiff paper board constructed from a single blank, the edges of which are overlapped and riveted or cemented together, or both, as at 38 in Fig. 2. These 110 containers are preferably shipped and handled in the flat or knocked down condition and after having been opened out into rectangular form, the bottom of the container is first completed by folding over the side flaps 39 and 40 and the end flaps as at 41, 115 120 125 130 135

said flaps all being cemented or riveted together, or both.

After the said flaps have been cemented to form the bottom of the carton, the frame ends which have been previously clamped together, as above described, are inserted or dropped down into place as shown in Fig. 3, the bottom mounts 42 on the lower ends of the head-end post portion 12 resting upon the 3-ply thickness of paper board formed by the overlapping of the flaps 39, 40 and 41. A strip 43 of relatively thin lumber and of width and length substantially equal to the cross sectional dimensions of the carton, is laid in the end of the package so as to rest upon the upper pair of clamps. Said strip 43 if desired, may be tacked to the clamps. After the strip 43 has been inserted, the side flaps 44 and 45 and the end flaps, as at 46, are cemented and folded in place, preferably clamping them down against the board 43 by any suitable pressure applying device until the cement is set sufficiently to enable the package to be handled without danger of the flaps springing away from each other.

In Fig. 7 we have illustrated the clamps as applied to a bedstead similar to the one previously described, but constructed of tubing of round instead of square cross section. Apart from the shape of the clamping blocks, which for the round tubing are made with semi-circular grooves, the details of construction and arrangement are substantially the same as previously described. The package herein described has a number of important advantages over previous methods of packing and shipping bedsteads. For instance, according to our method of packaging, the bedstead is shipped from the manufacturer in a sealed, substantially rigid outer container, which container may be marked with the name of the manufacturer, and also with the necessary data to identify the contents of the container. Such sealed package need not be opened by the distributor or retailer, and is intended to reach the consumer or user in the same condition as that in which it leaves the plant of the manufacturer. Hence, substitution of inferior articles is effectually eliminated.

Any damage in shipment will be disclosed by the condition of the container, fire hazard due to the use of excelsior or other inflammable packing material is materially reduced, and the merchandizing of the bedstead including the handling of same by the distributor and dealer is very much simplified. The home of the user is not littered up with excelsior when the bedstead is removed from the package, the surface of the finish is not injured by the packing and shipping process, and in addition thereto the character of the package is such that all persons handling the same are impressed with the value and high quality of its con-

tents, and, hence, causes the goods to be handled and treated in a much more careful manner than is the case where the same article is shipped in a crate made of rough lumber.

The described details of construction and operation are merely illustrative of a single phase of our invention, the scope of which should be determined by the appended claims, said claims being construed as broadly as possible consistent with the state of the art.

We claim:

1. As a new article of manufacture, a packaged finished bedstead frame comprising a head-end-panel having corner-posts provided with side-rail-connecting brackets, a foot-end-panel rigidly spaced from said head-end-panel, arranged parallel therewith and supported by said brackets, means for clamping together said panels in said spaced relation, said means projecting out beyond the outer boundaries of said panels, and a surrounding form maintaining container enclosing said panels, but having its walls spaced from the finished surfaces of said panels by said projecting means.

2. As a new article of manufacture, a packaged finished bedstead frame comprising a head-end-panel having corner-posts provided with side-rail connecting brackets, a foot-end-panel also provided with corner-posts rigidly spaced from the head-end-panel and arranged parallel therewith, spacing means mounted on said brackets for supporting the ends of the foot-end corner-posts thereby to bring the upper portions of the foot-end-panel and of the head-end-panel in substantial register, clamps for rigidly securing together said panels in said spaced relation, and a surrounding form maintaining carton enclosing said panels and having its walls spaced from the finished surfaces of the frame.

3. As a new article of manufacture, a packaged finished bedstead frame comprising a head-end-panel having corner-posts provided with side-rail-connecting brackets, a foot-end-panel also provided with corner-posts rigidly spaced from the head-end-panel and arranged parallel therewith, spacing means mounted on said brackets for supporting the ends of the foot-end corner-posts thereby to bring the upper portions of the foot-end-panel and of the head-end-panel in substantial register, clamps for rigidly securing together said panels in said spaced relation, and a surrounding form maintaining carton enclosing said panels, said clamps having parts projecting beyond the boundaries of the finished surfaces of the panels so as to prevent said finished surfaces from contacting with the walls of the container.

4. As a new article of manufacture, a

packaged, finished bedstead frame comprising a head end panel having corner posts provided with side rail connecting brackets, a foot end panel rigidly spaced from said head end panel, arranged parallel therewith, and supported by said brackets, means for clamping together said panels in said spaced relation, said means projecting out

beyond the outer borders of said panels and a paper-board container enclosing said panels, the walls of said container being spaced from the finished surfaces of said panels by said projecting means.
